UNITED STATES PATENT OFFICE.

HARRIE A. BALLARD, OF ASHLAND, MASSACHUSETTS, ASSIGNOR, BY MESNE ASSIGNMENTS, TO THE BOYLSTON MANUFACTURING COMPANY, OF BOSTON, MASSACHUSETTS, A CORPORATION OF NEW JERSEY.

LASTING-MACHINE.

1,131,983.

Specification of Letters Patent.

Patented Mar. 16, 1915.

Application filed March 16, 1904. Serial No. 198,420.

To all whom it may concern:

Be it known that I, HARRIE A. BALLARD, of Ashland, in the county of Middlesex and State of Massachusetts, have invented 5 certain new and useful Improvements in Lasting-Machines, of which the following is a specification.

This invention has relation to machines for lasting shoes, and more particularly to 10 that class of such machines known as "bed-lasters," in which the edge of the upper of a shoe is pulled over the inner sole at the toe and heel of the partially-formed shoe.

One of the objects of the invention is to 15 provide lasting and pulling-over mechanism so constructed as to subject the upper to a proper maximum tension, to cause it to assume the exact shape of the last, and further to crimp the edges of the upper regularly 20 and evenly, so as to distribute evenly on the inner-sole the bulk of material or stock over which the outer sole is to lie.

In the embodiment of the invention illustrated upon the drawings, which is the best 25 embodiment now known to me, the arrangement of the wipers is such that the wiping edges which surround the toe or heel portions of the upper contract simultaneously toward an approximate center and may be 30 given a series of contracting and expanding motions for the purpose of ironing the crimps in the leather.

The wipers are mounted upon heads or carriages which are movable toward and 35 from each other, the paths of movement of the carriages being fixed. The wipers have wiping movement relatively to the carriages, the direction of such wiping movement being fixed as to lateral variation but variable 40 vertically. The wipers are adjustable to various inclined planes relatively to their respective carriages to enable them to follow the planes of the bottom of the last. The shoe is supported between the carriages 45 by adjustable supports whose adjustability, in conjunction with that of the wipers, affords any desired relative arrangement whereby the toe wipers and heel wipers may be caused to act symmetrically on right 50 and left straight and crooked shoes. The shoe supports, of which there are two, are adjustable horizontally in directions transverse to each other, so that the last may be adjusted to arrange the median line of its

forepart and that of its heel-part in line 55 with the lines of movement of the wipers at the toe end and heel end. The shoe supports are also adjustable vertically and are forced upwardly by independent springs. Each of the supports may be depressed by 60 means of a suitable foot-treadle located conveniently with respect to the operator, the last, however, being held upward, as stated, by spring pressure, the force of which may be adjusted or varied, as desired. 65

The heads which carry the wipers are movable toward the last through the medium of a hand-wheel and gearing and when released are returned automatically to initial position by spring-actuated mechanism. 70

A machine embodying the invention possesses many features of advantage resulting from the construction and arrangement of the parts, as hereinafter described.

Referring to the drawings, which, as 75 stated, illustrate one embodiment of the invention—Figure 1 represents a front elevation of the machine, with the wiper-carrying heads in retracted position. Fig. 2 is a plan view of the same. Fig. 3 is a plan view 80 of the head which carries the toe wipers. A depressing tool or hold-down is shown in position to depress the shoe. Fig. 4 represents a longitudinal vertical section of the head shown in Fig. 3. Fig. 5 is a plan view 85 of the top or wiper-retaining plate which covers the head on the wipers and retains them in position. Fig. 6 illustrates in plan view a partially assembled shoe with the toe and heel heads in operative position. (In 90 this figure the retaining plate is omitted from the toe-wiping mechanism and the wipers and said plate from the heel-wiping mechanism.) Fig. 7 represents the two heads with the retaining plate omitted, and 95 shows the wipers as having wiped the upper over on the sole. Fig. 8 represents a vertical cross section of the head shown in Fig. 3. Fig. 9 represents a vertical cross-section of a portion of the toe-jack on line 9—9 of Fig. 100 1. Fig. 10 represents a vertical cross section on the line 10—10 of Fig. 1, and illustrates the jack which supports the heel and middle portion of a last. Fig. 11 is a longitudinal vertical section of the jack shown in 105 Fig. 10.

The frame of the machine is indicated at 10, and is provided with guides 11 11, at the

top thereof, at each end, which are in alignment with each other. Upon these guides are mounted the toe carriage 12 and the heel-carriage 13. These carriages carry the toe and heel wipers, as will be subsequently described, and are adapted to be moved toward and from each other by mechanism which will be explained. The main jack 14, which supports the heel-part of the last, is placed in transverse guides 15 in the head 151 of a vertically movable upright column 16. On the upper end of the jack is a stud or pin 140, pivoted at 141 in position to enter the aperture in the top of the last. This stud or pin has an arm 142 connected by a spring 143 to the head 151, the tension of the spring being adjustable by means of an eye-bolt 144 and a nut 145. The spring is provided for the purpose of rocking the pin or stud 140 forward so as to press the toe of the last upon the toe-jack, which is subsequently referred to. The column 1 is keyed in a transverse web 161 of the frame, and is threaded, as illustrated, to receive an adjustable nut 19 between which and the web 162 is placed a strong helical jack-supporting spring 18.

The column 16 may be depressed by an operator through the medium of a treadle 21, its upward limit of movement being variable through the medium of the nut 20 which is flanged to permit its easy rotation by the operative. By means of this nut 20 the position of the jack may be adjusted. The jack itself is transversely adjustable across the head 151 by a worm 152 formed or secured on a shaft 153, as best shown in Figs. 10 and 11. This worm engages complementary rack teeth on the base of the jack. A hand-wheel 154 is secured to the shaft 153 to provide for the easy rotation thereof to effect an adjustment of the jack. Thus the lateral adjustment of the jack and the heel end of the last, provides for so swinging the last, about the toe post as a center, as to bring the median line of the forepart of a crooked right or left shoe in line with the toe wipers, as will be explained more in detail. For very crooked lasts the rack may be elongated, to get a greater lateral movement of the heel jack.

The toe-jack is indicated at 22, being formed with a suitable head 221, upon which the toe portion of a last rests. It is internally threaded to receive the upstanding threaded post 23, the base of which is dovetailed into guides 25 formed in the head 251 of an upright column 26 similar to that at 16. The guides 25 extend longitudinally of the machine, so that the toe-jack may be adjusted according to the length of the shoe toward and from the main-jack. The column 26 is passed through the webs 161 162 and is threaded to receive the collar 29 which is similar to that at 19. A spring 28 is in-

terposed between said column and the web 162, the upward limit of movement of the column under the tension of the spring 28 being determined by the nut 30 which is similar to that at 20. A depressible foot-treadle 31 is connected to the lower end of the column 26 for the depression of the jack. The two treadles 21 31 are arranged in juxtaposition, so that the operator may easily depress one jack independently of the other, to effect the adjustment of the toe-end or heel-end of the last, as the case may be.

The toe-wiping mechanism is adjustable about two axes which are transverse to each other, the carriage itself being movable bodily toward and from the jack 22. This is in order that the wipers may be swung about a transverse axis to lie in, and there be held in, a plane substantially parallel to the bottom of the forepart of the last, and also adjusted about a longitudinal axis substantially parallel and close to the plane of the wipers or of the bottom part of a last supported by the toe jack or rest to conform to the transverse inclination of the bottom of the last. The base or body of the carriage is substantially box-like and is provided in its front and rear walls with semi-circular arc-shaped grooves or guides 40, as shown in Fig. 8. In these grooves or guides 95 extend the interlocking ribs or ends of a semi-cylindrical block or member 41, said member having on its periphery rack-teeth 42 for engagement by a worm 43, as shown in Fig. 4. The said worm 43 is on a shaft 100 44, which projects through the end-wall of the carriage and is equipped with a hand-wheel 45 by which it may be rotated. The rotation of the said worm moves the member 41 about an axis transverse to a last supported by the jacks. The member 41 is itself formed with curved guides or guide-ways 46 for the reception of correspondingly shaped interlocking ribs on a support or a member 47 which is substantially semi-cylindrical. The axis of the member 47 is longitudinal of the machine, and in the plane of the forepart of the inner sole of a partially lasted shoe resting upon the toe support, whereas the axis of the member 41 is transverse with relation to the machine, all as shown in Figs. 4 and 8. The member 47 is formed in its periphery with rack-teeth 48 which are engaged by a worm 49 on a shaft 50, said shaft being journaled in 110 sockets or slots 51 51 in the ends of the member 41. The said shaft is equipped at its front end with a hand-wheel 52. The upper portion of the member 47 is flat and to it is secured the base-plate 53 of the head. The two semi-cylindrical members 41 and 47 with their adjusting devices enable the wipers carried thereby to lie in any plane required by the sole of the last.

The carriage itself is formed in its base 130

with rack-teeth 55 which are engaged by a pinion 56 on a shaft 57 extending from front to rear of the machine and journaled in the frame thereof. On the front end of the 5 shaft is a hand-wheel 58 having in its periphery ratchet-teeth 59 for engagement by a lazy-pawl 60. This pawl is held in engagement with the wheel by a spring 61, but is formed with an arm 62 which may 10 be engaged by the knee of the operator and moved to disengage the pawl from the hand-wheel. The carriage is automatically returned to initial position by means of a bell-crank lever whose long arm 63 is connected 15 to the carriage by a curved link 64 and whose shorter arm 67 is thrown upward by the spring 65. The spring 65 is coiled about a pin 66 connected to the arm 67 and projecting through a lug 68 on the frame. The 20 end of the pin 66 is threaded to receive a cushioned nut 69 which may be adjusted to limit the retrograde movement of the carriage. This adjustment of the nut 69 provides for the carriage moving backward but 25 a short distance when small shoes are being lasted, and saves the operator the exertion of moving the carriage from its extreme outward limit of movement each time the wipers are to be actuated.

30 The base-plate 53 of the wiper-head is provided at its inner end with upwardly projecting lugs 70 in which is trunnioned the wiper support 71, by means of the pintle 72 (see Fig. 4). The wipers 75 75 are coupled or hinged together at 76, as shown in 35 Fig. 6, and they lie in a recess between the support 71 and a top-plate 77. The plate itself is removably held in place by a latch 78 pivoted at 79 and adapted to engage the 40 notched end of a pin 80 that projects upwardly from the wiper-support through the top-plate. A handle 81 is attached to the top-plate for its convenient removal. The wipers are formed with curved wiping edges 45 a a, and they project beyond the recessed portion of the wiper-support. They are adapted to be moved bodily and at the same time swung about their coupling 76 by means of a slide 82 arranged in a guide 83 50 formed in the wiper-support 71. The said slide 82 has pivoted to its ends two links 84 84 whose rounded heads 85 85 fit removably in sockets 86 in the rear parts of the wipers 75. Near their outer edges 55 the wipers are provided with curved cam slots 87 into which project guide-rolls 88 journaled on upstanding pins 89 on the wiper support 71. By moving the guide 82 forward, the wipers 75 75 may be caused to 60 move bodily in the same direction and also to swing inward about their coupling 76, as illustrated in Figs. 6 and 7.

65 The wiper-support 71 is trunnioned at 72 upon the base plate 53 and has a limited oscillatory movement on a substantially

horizontal axis, or on an axis parallel with the base-plate, this movement being effected by the same device which serves to actuate the slide 82. Preferably a hand-lever 90 is employed for this purpose. The said handle 70 has a ball and socket connection with the slide 82, and its rear end is fulcrumed upon a pin 91 which passes through a slot 92 in an arm 93, as shown in Fig. 3. The said arm is connected to the head 53 by a 75 substantially horizontal pintle 94, arranged parallel to the lines of movement of the slide 82. The handle-lever 90 may therefore not only be rocked about its fulcrum 91, to advance and retract the wipers, but 80 also may be moved up and down about its fulcrum or pintle 94 to swing the wiper or support about its trunnions.

85 Since the pressure of the wipers upon the shoe tends to force their operative ends upward, an abutment must be provided to limit the movement about the axis of the pintle 72. Hence I employ an adjustable abutment screw 150 which is passed through a web projecting laterally from the guide 90 83, so as to bear against the base plate 53 of the head, as shown in Fig. 8. Ordinarily this abutment is adjusted as shown, so that, when it engaged the plate 53, the axis of the slide 82, to be described, is parallel with 95 and close to the axis of transverse tilting movement of the wiper support.

95 The heel-wiping mechanism is mounted upon a head 100 between which and the carriage 13 is an adjusting mechanism similar 100 to that of the toe-wiping mechanisms previously described, and identified by the same reference characters. The carriage 13 is advanced by the hand wheel and rack gearing, and withdrawn by spring-actuated 105 mechanism, similar to those employed in connection with the toe-wiper carriage, the same reference characters being used to indicate such parts of the heel-carriage mechanism as are duplicates of corresponding 110 parts of the toe-carriage mechanism.

115 The wipers 101 102 have their operative edges properly curved to conform to the heel portion of the shoe, and they are operated by mechanism similar to that employed for operating the toe-wipers. In fact, the heel-wiping mechanism and toe-wiping mechanism are duplicates except that the heel-wiping mechanism has a band for pressing the upper against the sides and 120 back of the heel-part of the last.

125 Referring to Fig. 6, it will be observed that the wiper-support 711 is recessed in its upper surface to receive two bars 104 to the projecting ends of which are pivoted triangular blocks 105 which support the flexible heel-band or clamp 106. Said band or clamp may be formed of leather or any other suitable flexible material. The two bars 104 104 are pivoted to a cross-bar 103 130

which is fulcrumed intermediate of its end in a socket 107, and which has a limited swinging movement about its socket by reason of the formation of the recess in the wiper-support in which it is placed. The 5 two bars 104 104 being pivoted to the cross bar, may swing toward and from each other at their ends, and one of said bars may move forward as the other is retracted. This 10 construction provides for the band 106 closely clamping the heel end of the last so as to bind the upper firmly against the last whether the shoe be right or left.

The operation of the machine is as follows:—The last with the insole and the 15 upper assembled for lasting, is placed in the machine upside down, as shown in Fig. 1. It is placed upon the stud or pin 140 and the said pin is rocked about its fulcrum 141 to permit the toe of the last to be placed 20 upon the toe-jack where it is securely held by the tension of the spring 143. The shoe is then adjusted so that the median line of its heel-part shall be in line with the wiping 25 movement of the heel-wiping mechanism. This is done by turning the hand wheel 154 and by shifting the toe of the shoe laterally. The hand wheel 154 imparts bodily lateral movement to the last; and shifting the toe 30 of the shoe, as stated, swings the shoe about the axis of the pin 140 upon which the last is mounted. The shoe and wiping mechanism may thus be so related that the wipers will act symmetrically upon the two sides 35 of the heel-part of either a right or left shoe, whether the median line of the heel-part is in line with or out of line with the median line of the forepart. The heel-wiping mechanism is then adjusted so that 40 the wipers lie in a plane substantially parallel to the plane of the heel seat. The jack nut 20 is adjusted to position the heel seat slightly above the plane of the wipers; and when the carriage 13 has been locked in 45 operative position to set the band 106 against the shoe, the actual wiping-over may be performed. Since the heel seat is above the plane of the wipers, the jack must be depressed by the treadle 21 in order 50 to enable the wipers to act. The operative, with one foot upon the treadle and one hand upon the heel-wiping lever 90, may depress the one just enough to permit wiping movement of the other. When the upper 55 has been wiped over by the heel wipers as shown by Fig. 7, the treadle 21 may be released to permit the jack spring 18 to force the wiped-over and pleated material against the under side of the wipers. The 60 operating lever 90 may now be released, leaving the heel wipers in the position shown by Fig. 7, and the operative may drive suitable nails to secure the wiped-over material to the heel seat. When the 65 wiped-over material has been suitably se-

cured, the wipers may be retracted, and their carriage 13 may be retracted to the position shown by Figs. 1 and 2.

A large proportion of shoes are crooked. That is to say, the median line of the forepart and that of the heel-part are at an angle relatively to each other. In view of such formations, the shoe supports are adapted to be adjusted so that both wiping mechanisms may act symmetrically upon 75 the two sides of the two ends of the shoe.

If it is impossible to last both ends at the same time because of an angular relation of the forepart and heel part of the shoe, the 80 ends may be lasted one at a time, each end-wiping mechanism being retracted when the other is in use. After the heel end has been lasted as aforesaid, the shoe may be adjusted so as to cause the median line of its forepart to coincide with the line of wiping movement of the toe wipers. This is done by again turning the hand wheel 154 and by shifting the toe of the shoe laterally. In addition to adjusting the shoe 85 with reference to the median line of its forepart, the toe wipers are to be adjusted so that they will lie in a plane substantially parallel to the plane of the toe end of the last. The jack nut 30 is adjusted to position 90 the toe end of the shoe slightly above the toe wipers in order to insure sufficient pressure of the wiped-over and pleated toe portion against the under side of the toe wipers when the wipers are advanced as shown by Fig. 7. In this respect the operative 95 manipulates the treadle 31 and the toe-wiping lever 90 in conjunction with each other just as the treadle 21 and heel-wiping lever are operated as hereinbefore described. In each case the operative is 100 able to keep the wipers pressed downwardly upon the work by upward pressure upon the handle 90, the wipers being capable of 105 tilting about the trunnions 72 while acting upon the shoe.

When the upper has been wiped over the toe portion as shown by Fig. 7, it may be secured, if desired, by a strip of flexible material α , such as tape. Figs. 1 and 2 show a spool 110 upon which a strip α of indeterminate length is wound. As shown by Fig. 7, a short piece of tape is laid between the wipers and the pulled-over portion. It is drawn taut and secured by tacks. If desired, the tacks may be driven between the 115 edge of the wipers and the edge of the pleated portion of the upper, and the tape may be omitted.

I have illustrated a shoe which is nearly straight; that is to say, the median line of 125 its forepart is nearly in line with the median line of its heel-part; and I have shown the heel-wiping mechanism and toe-wiping mechanism acting simultaneously upon the shoe. It is to be understood, however, that 130

the two end-wiping mechanisms are shown acting simultaneously only because the shoe illustrated permits simultaneous action and that whenever the shape of the shoe requires 5 independent operation of the end-wiping mechanisms the latter will be used independently, and the shoe will be adjusted as hereinbefore described to place the median line of the heel-part in the desired position 10 for operating upon the heel and to place the median line of the forepart in the desired position for operating upon the toe.

An advantage gained by pivoting the wipers and their supporting mechanism to 15 swing about the axis of the transverse pivot 72 is that the operative may, by means of the operating hand lever, swing the operative portions of the wipers downward, below the plane of the sole, so as to engage the material around the toe of the last, and wipe it upward, so as to draw the upper forwardly, until the wipers reach the plane of the bottom portion of the end of the sole, after 20 which, by means of the same handle he may 25 move the wipers bodily along the median line of that part of the sole, at the same time causing the curved edges of the wipers to wipe the fringe of the upper over the marginal portions of the last or inner sole. 30 This may be repeated until the upper is drawn taut and properly lasted. If desired, however, this drawing action of the wipers may be accomplished by drawing the toe jack downward by the appropriate treadle, 35 and forcing the wipers forward to engage the upper around the toe, and then relieving pressure upon the treadle to permit the spring to move the toe jack upward.

It is apparent, from the foregoing description, that my invention is possessed of numerous advantages over earlier machines of the same general type.

First. The operator is not compelled to hold the sole to the wipers by the pressure 45 of his foot, as hitherto necessary, since that is accomplished by means of the springs which surround the jack-column. The operator may, if he desires, depress the jacks sufficiently to insert the ends of the last under the edges of the wipers, after which his foot may be removed from the treadles. The adjustability of the two jacks, and the 50 relative adjustability of the last, together with the other adjustments hereinbefore described in detail, enables the operator to locate the parts in position to cause the wipers accurately to conform to the toe and heel portions of the last.

Second. The pivoting or trunnioning of 60 the wiper support on lines substantially transverse to the lines of bodily movement of the wipers enables the operator to draw the upper over the toe and heel of the last, and to wipe it in place by a bodily movement of said wipers prior to the contracting

movement across the face of the insole. These movements of the wipers are accomplished by a single hand-lever which has a universal movement as described.

Third. The machine is compact, has no 70 delicate parts, and is strong and durable.

Fourth. Provision is made for the accurate and automatic adjustment of the band to cause it to conform accurately to the last.

There are other advantages which will be 75 apparent to those skilled in the art to which this invention relates, but which it is unnecessary to detail. It will be understood that the wipers are removable whereby they may be replaced by others whose operative 80 edges conform to the shape of the shoe to be lasted.

Having thus explained the nature of the invention, and described a way of constructing and using the same, although without 85 attempting to set forth all of the forms in which it may be made, or all of the modes of its use, I declare that what I claim is:—

1. A lasting machine comprising end wiper mechanism, a vertically movable reciprocal post or column having a flat head, means for raising and means for depressing said post or column, and a jack dovetailed on said head and bodily adjustable transversely thereon whereby said jack 95 may be adjusted laterally with relation to the end wiper mechanism without varying its angularity thereto.

2. In a lasting machine, a frame, end wiping mechanisms, a main jack, a toe jack, a 100 movable column for each jack, means on each column for adjustably holding the respective jacks, fixed bearings in said frame for said columns, adjustable members for limiting the movement of the columns toward the wiping mechanisms, and a pair of treadles each pivotally connected directly with one of the columns.

3. A lasting machine comprising a carrier, a wiper-carrying head, two members 110 interposed between said carrier and said head and respectively movable about axes extending at right angles to each other, each of said members having segmental gear teeth, and transversely arranged worms for 115 adjusting said members and engaged with the teeth thereof.

4. A lasting machine comprising a support, and three tilting members superimposed one upon another, all being mounted 120 upon said support, the axes of the first and third tilting members being transverse to the axis of the intermediate tilting member, a manually operative member mounted on said intermediate member, wiping means 125 mounted upon the third tilting member, and means connecting said manually operative member and said wiping means for moving the latter relatively to the third tilting member, said means engaging the 130

third tilting member and adapted to move the same relatively to said intermediate member.

5. A jack, a base member movable toward and from the jack, coacting wipers, a support for said wipers, means for pivoting said support to said base member to permit said support to tilt about an axis transverse to said lines of movement of the base member and closely adjacent the under sides of the wipers, an operating member mounted on said base member, and means connecting said operating member to the wipers and to said support, so constructed and arranged that said operating member may tilt the support and operate said wipers whereby the wipers may be caused to draw the upper across the end of the last and then wipe the upper across the bottom of the last.

20 6. A lasting machine comprising coacting wipers, a support therefor, a base member on which said support is pivoted to move about a transverse axis in the rear of the operative edges of the wipers, an operating lever, a universal joint connecting said lever with said base member, and means connecting said lever with said wipers and said support, so constructed and arranged that an operator by the manipulation of said lever may tilt the support and operate the wipers for the purpose set forth.

7. A lasting machine comprising a support having a guide, a slide movable in said guide, coacting wipers on said support connected to said slide, a head, means for pivotally mounting said support on said head, a lever having a ball-and-socket connection with said slide, and a universal joint connecting the end of said lever to said head.

40 8. A lasting machine comprising a pair of coacting wipers, a support for said wipers recessed below said wipers, substantially parallel bars supported by the recess in said support, a band or clamp connected to the ends of said bars, and a cross bar pivotally connected to said substantially parallel bars, and having a rocker bearing intermediate of its ends upon the wall of said recess.

9. A lasting machine comprising a support, and three tilting members superimposed one upon another, all being mounted on said support, means for moving the first tilting member to various positions, means on the first tilting member for moving the second tilting member to various positions, means on the second tilting member for moving the third tilting member to various positions, and wiping means mounted on said third tilting member.

60 10. A lasting machine comprising a support, and three tilting members superimposed one upon another, all being mounted on said support, means on said support for positioning the first tilting member, means on the first tilting member for positioning

the second tilting member, wiping instrumentalities movably mounted on the third tilting member, and means on the second tilting member adapted to position the third tilting member and operate the wiping instrumentalities.

11. A lasting machine comprising a jack, a carriage movable toward and from the jack, a base member supported upon the carriage and adjustable about an axis longitudinal of the lines of movement of said carriage, means for positively positioning said base member about said axis, a wiper support pivoted to said base member on a transverse axis, wipers supported unyieldingly upon said base member, an operating lever pivotally mounted upon said base member, and connections between said operating lever, said wipers and said base member so constructed and arranged that said lever may be manipulated to tilt the base member and operate said wipers.

12. A lasting machine comprising heel and toe wiper mechanisms, a toe jack, and a main or heel jack, located between said wiper mechanisms, a supporting guideway for the toe jack extending longitudinally of lines connecting the end wiper mechanism a supporting guideway for the main or heel jack extending transversely of said lines, whereby the toe and heel jacks may be adjusted bodily in intersecting lines to place either end of a shoe to be lasted in alinement with the corresponding wiping mechanism, and means including a treadle for effecting a vertical relative movement of each guideway and jack thereon and the corresponding wiper mechanism, independently of the other.

13. In a lasting machine provided with wipers, a reciprocating carriage for the wipers, wiper-actuating mechanism mounted on said carriage, means under the control of the operator for moving said carriage toward the last, a lock for locking said means to prevent recession of the carriage, said lock being under control of the operator to be tripped thereby, a spring, a lever, and a link connecting said lever to the carriage and arranged to store power in said spring when the carriage is moved toward the last, whereby when the lock is tripped the spring through the medium of said lever will withdraw the carriage from the last.

14. In a bed lasting machine, toe-wiping mechanism, heel-wiping mechanism, and work-supporting instrumentalities located between said wiping mechanisms comprising a toe support and a heel support, said toe support being adjustable toward and from the toe-wiping mechanism longitudinally of a line connecting said mechanisms, and said heel support being adjustable transversely of said line, whereby a right or left crooked shoe may be adjusted horizontally and angu-

larly to position it with the median line of its forepart in alinement with the median line of the toe-wiping mechanism.

15. In a bed lasting machine, toe-wiping mechanism and heel-wiping mechanism movable in rectilinear lines toward and from each other and held against movement transverse to said lines, and shoe-supporting supports arranged between said mechanisms, one of said supports being fixed as to lateral movement but movable longitudinally of the shoe, and the other being movable laterally to adjust the forepart and heel-part respectively of the shoe with relation to the aforesaid lines of movement of said wiping mechanisms, and means for adjusting said supports as described whereby a right or left crooked shoe may be adjusted horizontally and angularly to position it with the median line of its forepart in alinement with the median line of the toe-wiping mechanism.

16. In a bed lasting machine, toe-wiping mechanism and heel-wiping mechanism movable toward and from each other and arranged so that their lines of movement toward and from each other are fixed, a toe support for the toe of a shoe arranged between said wiping mechanisms, and a heel support for said shoe, said toe support being fixed as to movement laterally of the shoe and movable longitudinally thereof, said heel support being movable laterally to adjust the forepart and heel-part respectively of the shoe with relation to said lines of movement of said wiping mechanisms, whereby a right or left crooked shoe may be adjusted horizontally and angularly to position it with the median line of its forepart in alinement with the median line of the toe-wiping mechanism, in combination with treadle-operated means for effecting a relative vertical movement of each of said supports and its corresponding wiping mechanism.

45 17. In a bed lasting machine, toe-wiping mechanism and heel-wiping mechanism movable toward and from each other and arranged so that their lines of movement toward and from each other are fixed, a toe support for the toe of a shoe arranged between said wiping mechanisms, and a heel support movable about a pivot and also bodily movable laterally of said lines of movement to adjust the forepart and heel-part respectively of the shoe with relation to said toe-wiping mechanism and heel-wiping mechanism, the axis of said pivot extending laterally of the shoe to permit longitudinal adjustment of the shoe with relation to the adjustable toe support.

60 18. In a bed lasting machine, toe-wiping mechanism and heel-wiping mechanism movable toward and from each other and arranged so that their lines of movement toward and from each other are fixed, a toe

support and a heel support for the toe and heel respectively of a shoe arranged between said wiping mechanisms, and means permitting said supports to be relatively adjusted in lines transverse to each other, whereby the forepart of a crooked shoe may be positioned for symmetrical engagement by said toe-wiping mechanism and the heel-part of said shoe positioned for symmetrical engagement by said heel-wiping mechanism. 75

19. In a lasting machine, the combination with a toe support, of a lasting head having wiper plates adapted to lay the upper over the bottom of the shoe resting on said support, means for effecting a relative vertical movement of said head and said support, arc-shaped interlocking rib and groove bearing confections located between the lasting head and wiper plates curved to permit movement of said plates about an axis extending lengthwise of the bottom of the shoe to be lasted and disposed with relation to the wiper plates to furnish an unyielding support for said plates when pressed upon the bottom of the shoe. 85

20. In a lasting machine, the combination with a shoe support, of a carriage provided with wiper plates arranged to move over the bottom of a shoe to be lasted, said carriage having a base, an interlocking arc-shaped rib and groove bearing connection located between the wiper plates and the base to permit lateral rocking movement of the wiper plates and direct such movement about an axis extending lengthwise of the bottom 95 face of a shoe resting on said support, and means for effecting and maintaining the said lateral adjustment of said wiper plates. 100

21. In a lasting machine, the combination of shoe supporting means, a base member 105 provided with lasting means, a carriage, said carriage and base member having laterally extending arc-shaped interlocking rib and groove connections curved to permit rocking movement of said base member about an axis extending lengthwise of a shoe resting on said shoe supporting means, and gear and segment connections for adjusting said base member about said axis.

22. A lasting machine comprising toe lasting means, a laterally fixed toe rest, a frame in which the lasting means and toe rest are mounted, a support for the lasting means, and a connection located between said frame and said support, and including ribs and 115 grooves curved to permit said support to move about an axis extending substantially parallel with the plane of the bottom face of a last sustained on the toe rest. 120

23. A lasting machine comprising in combination, lasting means, a shoe support, a carriage movable toward and from the shoe support, a support on the carriage for the lasting means, and an interlocking arc-shaped rib and groove connection located 125 130

- between said support and said carriage arranged to permit lateral rocking movement of the lasting means and to direct that movement about an axis extending lengthwise of the shoe and located substantially parallel to the plane of the bottom face of a shoe sustained on said support.
24. A lasting machine comprising, in combination, means for supporting a shoe in position to be lasted, lasting means, a laterally rocking support for said lasting means, a carriage for said support, said support and carriage having transverse interlocking arc-shaped ribs and grooves formed and arranged to permit the lasting means to be adjusted about an axis extending lengthwise of the shoe, and means for moving the lasting means to conform the shoe upper to the last.
25. A lasting machine having in combination, a shoe support; lasting means, a carriage, a support for the lasting means on said carriage, means arranged to permit tilting of the lasting means and its support about an axis extending transversely of the last, and correspondingly curved guideways on the carriage and support and arranged to permit the lasting means to rock laterally to adjust said lasting means in accordance with different transverse inclinations of the last bottoms.
26. A lasting machine having in combination, lasting means, a support on which the lasting means are sustained, a carriage on which the support is supported for lateral rocking movement, a transverse arc-shaped guideway supported by the carriage, transverse guiding devices on the support and movable in said arc-shaped guideways, and means for rocking said support to position the lasting means in accordance with the transverse inclination of the last bottom.
27. A lasting machine having in combination, lasting means constructed and arranged to act upon a shoe simultaneously at opposite sides of the end portion of the last, means for supporting the shoe, means for sustaining the lasting means, and a sliding connection between the lasting means and its sustaining means including segmental curved guideways for the moving part curved in the arc of a circle to permit the lasting means to be adjusted about an axis extending longitudinally of the last.
28. A lasting machine comprising, in combination, lasting means comprising a means shaped to embrace an end portion of a shoe, and a supporting mechanism therefor including a member having a segmental lower bearing face, a support for said member having a correspondingly curved seat for the member, and means for angularly adjusting the member in said seat about an axis extending longitudinally of the last.
29. A lasting machine comprising, in com-

bination, lasting means comprising a means shaped to embrace an end portion of a shoe, and a supporting mechanism therefor including a member having a lower segmental bearing face curved about an axis extending lengthwise of the last, and a support having a correspondingly curved seat for the member to permit angular adjustment of the lasting means transversely of the shoe.

30. A lasting machine having, in combination, lasting means comprising a means shaped to embrace an end portion of a shoe, and a supporting mechanism therefor including a member having a lower segmental bearing face curved about an axis extending lengthwise of the last, and a support having a correspondingly curved seat for the member, and connections between the member and the lasting means for effecting angular adjustment of said lasting means about said axis.

31. An apparatus of the class described having, in combination, means for supporting a shoe in position to be lasted, lasting means, a member for supporting the lasting means, a support for said member, means arranged to permit tipping of the lasting means about an axis extending transversely of the last, and segmental bearing portions and correspondingly curved guideways formed on the member and the support and arranged to permit the lasting means to move laterally to adjust said means in accordance with different transverse inclinations of last bottoms.

32. An apparatus of the class described having, in combination, lasting means including wiper mechanism, a member upon which the lasting means is sustained, a support upon which the member is carried for lateral rocking movement, a transverse arc-shaped guideway not more than 180° in extent formed in the said support and located entirely below the lasting means, a transverse curved guiding device on the said member and movable in the arc-shaped guideway, and means for rocking the member to position the lasting means in accordance with the transverse inclination of the last bottom.

33. In a machine of the class described, the combination with a shoe support, and lasting means comprising wiper plates and means for actuating them to do their work, a sliding member for supporting the lasting means, a support on which the member is movable for angular adjustment of the lasting means, and an interlocking arc-shaped tongue and groove connection between the member and the support having its axis of movement longitudinal of the shoe being lasted.

34. A lasting machine, comprising the combination of lasting means shaped to embrace the end portion of a shoe and a sup-

- porting mechanism therefor, including a member having a segmental lower bearing face, a support for said member having a correspondingly curved seat located entirely 5 below the lasting means and engaging the face of the member, and means for angularly adjusting the member upon said seat about an axis extending longitudinally of the last.
35. A lasting machine having a tipping wiper carrier, a relatively stationary support, a segmental gear on said carrier, means intermeshing with said gear for moving the same, and a sliding interlocking 10 tongue and groove connection between said wiper carrier and said support to permit 15 tilting movement about the axis of said gear.
36. In a lasting machine, the combination 20 of shoe-supporting means, a member provided with lasting devices, a support, said member and support having a sliding connection consisting of segmental ribs and 25 grooves curved about an axis extending substantially parallel to the plane of the bottom of the shoe and extending in a direction lengthwise of the shoe, and means for locking the member in adjusted position.
37. A lasting machine having in combi- 30 nation, a jack for supporting the toe of a last and about which the last may be moved when resting thereon, a toe-lasting mechanism, a heel jack, and a heel-lasting mechanism, said lasting mechanisms being bodily movable in the median lines of the machine 35 toward and from each other and toward and from a last supported by said jacks, a separate treadle and mechanism actuated thereby for effecting a relative vertical bodily movement of each jack and the corresponding lasting mechanism, each lasting mechanism comprising wiper plates, and means for rocking said plates about an axis longitudinal of the machine, and means for adjusting said jacks, one in right lines toward 40 and from the corresponding lasting mechanism and the other in lines transversely perpendicular thereto, whereby the shoe to be lasted may be placed in proper position to be lasted and the wipers adjusted to the 45 plane of the bottom of the end of the last adjacent thereto.

In testimony whereof I have affixed my signature, in presence of two witnesses.

HARRIE A. BALLARD.
